BROACHING MACHINE

Francis J. Lapointe, Ann Arbor, Mich., assignor,
by mesne assignments, to American Broach &
Machine Co., Ann Arbor, Mich., a corporation of
Michigan

Application April 18, 1939, Serial No. 268,535

24 Claims. (Cl. 90—33)

More particularly, the invention relates to a machine for cutting gears and other externally toothed and splined elements by the use of broaching tools, it being the general object of the invention to provide a new and improved machine adapted to cut all the projecting portions of such an element by a single stroke of a plurality of broaching tools.

Another object is to provide such a machine embodying means for supporting the work blank from which the element is formed and the tools and for guiding the tools accurately with respect to the blank during the cutting operation.

Another object is to provide such a machine embodying a work blank support and tool guiding fixture provided with tool guiding surfaces supported integrally with the work support and laterally opposite the point of cutting.

Another object of the invention is to provide a new and improved means for supplying cutter coolant to a plurality of broaches operable to cut a gear.

Another object is to provide such a machine with automatically operable means for ejecting a finished work piece from the machine.

Further objects will become readily apparent from the following detailed description taken in connection with the accompanying drawings, in which:

Fig. 1 is a front elevation of a preferred form 30 of the invention.

Fig. 2 is a vertical section approximately along the line 2—2 of Fig. 1.

Fig. 3 is an enlarged fragmentary vertical section approximately along the line 3—3 of Fig. 2.

Fig. 4 is a horizontal section approximately along the line 4—4 of Fig. 3.

Fig. 5 is a fragmentary elevation partly in section along the line 5—5 of Fig. 7.

Fig. 6 is a horizontal section approximately 40 along the line 6—6 of Fig. 3.

Fig. 7 is a horizontal section approximately along the line 7—7 of Figs. 3 and 5.

Fig. 8 is a plan section approximately along the line 8—8 of Fig. 1.

Fig. 9 is a horizontal section approximately along the line 9—9 of Fig. 3.

While there is disclosed in the drawings and hereinafter described in detail a preferred form of the invention, it is to be understood that the invention is not limited to the particular construction shown. It is contemplated that various changes may be made by those skilled in the art without departing from the spirit and scope of the appended claims.

In the form chosen for purposes of disclosure, the invention is embodied in an upright or vertical machine (Figs. 1, 2 and 8) having a column or frame 20 formed with a base pan 21 at its lower end and a pair of laterally spaced parallel ways 22 which extend vertically along opposite sides of the frame. A wall 23 extends vertically within the frame so as to divide it into a rear compartment 24 and a front compartment 25 and reenforcing webs 26 are provided between the wall 23 and ways 22. Gibs 27 are secured to the ways 22 by means of bolts 28 and cooperate therewith to form guideways for a tool supporting head 29 which has integral side ribs 30 fitted to slide therein. The head 29 is arranged to be reciprocated on the ways 22 by means including a pair of piston and cylinder devices, the pistons 31 of which are secured to the head 29 by means of piston rods 32 and the cylinders 33 of which are hung from a work plate 34. The work plate is supported on a pair of brackets 35 secured to the frame 20. It is contemplated that the cylinders will be supplied with a fluid under pressure from a suitable pump and under the control of valves (not shown) which will cause a slow or feed movement of the head 29 upwardly and a more rapid return or traverse movement of the head downwardly. The hydraulic pump and circuit are well known in the art and form no part of the present invention.

The invention relates more particularly to the means for supporting a plurality of tools and a work blank during a broaching operation which cuts all the teeth of a gear on the work blank in a single stroke. The tool supporting means will be described first.

As shown in the drawings and more particularly Figs. 1, 2 and 3 thereof, the tool head 29 has a horizontally extending portion 29' to which a tool holder or pull head 40 is secured. This pull head is arranged to grasp the upper ends 41 of a plurality of broaching tools 42 and pull the tools upwardly through a broaching stroke when the head 29 is moved upwardly. As shown most clearly in Figs. 3 and 4, the pull head 40 comprises a tubular member or stem 43 which has a reduced portion 44 positioned in a bore in the tool head portion 29' and is secured in place by a nut 45 threaded on the upper end thereof. The lower end of the stem is enlarged at 46 and provided with a plurality of annularly arranged radially extending slots 47 for receiving the upper ends 41 of the tools 42. The slots 47 are 55 intersected by an upper annular recess 48 and

also by a lower annular recess 49. A split ring 50 is secured in the upper recess 48 to serve as an abutment or stop member for the upper ends of the tools 42. A plurality of arcuate or segmental jaws 51 (herein eight in number) are positioned in the lower recess 49 and are movable radially from an outer position as shown in Figs. 3 and 4 to an inner clamping position wherein the jaws engage in recesses 52 in the outer edges of the upper ends 41 of the tools 42. The segmental jaws 51 are preferably provided with beveled cam surfaces 53 and 54 to facilitate operation thereof outwardly by beveled cam surfaces 55 and 56 on the upper tool ends respectively. The jaws are also provided with beveled cam surfaces 57 to facilitate operation thereof inwardly to a clamping position by an annular beveled cam surface 58 on a clamping ring 59. This ring is slideable up and down on the outer surface of the enlarged portion 46 of the chuck stem 43 between an upper position determined by the engagement of an abutment surface 60 on the ring with the lower surfaces of the jaws 51 (in which instance the jaws are released and the tools withdrawable) to a lower position determined by a stop ring 61 secured to and extending outwardly from the lower end of the clamping ring 59. When the clamping ring is moved downwardly, the cam surface 58 acts against the cam surfaces 57 to move the jaws inwardly to their clamping position. Preferably the recesses 52 in the upper tool portions 41 are of a greater dimension vertically than the jaws to insure proper interengagement.

The clamping ring 59 is arranged to be moved to its jaw unclamping position as shown in Figs. 3 and 4 by means of a pair of pins 62 upstanding from the work plate 34. When the tool head 29 and the tools are completing a downward stroke, the clamping ring 59 engages the pins 62 and moves to its upper position. The tools may then be drawn downwardly and disengaged from the chuck by an elevator designated generally 63 in which the lower ends of the tools are supported, as hereinafter described. In Figs. 3 and 4, the parts are in the positions assumed after a work blank W has been placed on a splined work arbor 64 and the tools 42 have been elevated to a position in which they are engageable by the chuck jaws 51. As the tool head 29 starts its upward movement (with the tools following due to continued operation of the elevator 63), the clamping ring 59 is moved downwardly to its tool clamping position by means of a pair of plungers 65 slidably mounted in bores in the head portion 29' and pressed downwardly by coiled springs 66.

The elevator 63, as illustrated in Figs. 1 to 3 and 9, comprises a member 67 slideable vertically on a pair of laterally spaced rods 68 secured at their lower ends in a base block 69 and joined at their upper ends by a cross member 70. The elevator member 67 is operable by means of a piston 11 (Fig. 2) which is mounted on the upper end of a piston rod 72 and is slideable in a cylinder 73 formed integrally with the member 67. The piston rod 72 is anchored at its lower end in the base block 69 and may be provided with two passages for supplying fluid under pressure to the opposite ends of the cylinder 73 in a manner well known in the art.

The broaching tools 42 are secured at their lower ends in a retaining means comprising a bushing 75 and a pair of split-ring clamping members 76. The bushing 75 has an outwardly extending lower flange 77 on which the lower ends

of the tools 42 and the clamping members 76 rest, and has also an upper outwardly extending flange 78 which is provided with a radially extending slot 79 for each tool. An intermediate 5 annular rib 80 on the bushing engages in notches 81 in the tools. The slotted upper flange serves to locate the tools in accurately spaced relation around the bushing. The clamping members 76 have ears 82 secured together by screw devices 83.

When the tools are supported on the elevator 63, the retaining means 75, 76 rests on a centering block 84 which is carried on a forwardly extending shelf or bracket 85 on the elevator. The 15 block 84 has a conically shaped upper end which fits into the lower end of the bushing 75, as shown in Fig. 1, so as to center the bushing thereon, and also has a bifurcated portion 86 into which one set of ears 82 fits so as to maintain 20 the proper angular position of the lower ends of the tools.

In broaching articles such as gears, it is necessary to obtain an unusually high degree of accuracy so that the teeth of the gears are uniform and properly spaced. It is an important 25 object of this invention to provide means for insuring accuracy in the broaching of the gears, and this object is attained largely by the structure for supporting the work blank W and for guiding 30 and backing up the individual teeth forming broaching tools immediately adjacent the work blank. This part of the invention will now be described.

The tool guiding and work supporting means is 35 herein shown in the form of a fixture mounted on the work plate 34 and comprises an annular member 90 (Figs. 3, 5, 6, and 7), an arbor supporting member 110 positioned centrally thereof, a lower ring 120 surrounding a reduced portion of 40 the annular member 90 and the work arbor 64.

The annular member 90 has an upper portion 45 91 fitted within a bore 34' in the work plate 34, an outwardly extending flange 92 held against the lower surface of the work plate by a plurality of screw devices 93 and a plurality of downwardly and inwardly extending web portions 94 wedge shaped as shown in the left hand half of Fig. 7 so as to form radially extending guide slots 95 for the broaching tools 42. The inner cylindrical 50 wall 96 of the annular member 90 forms a guide surface for the outer edges of the broaching tools and backs up the tools so that they cannot move radially outwardly of the fixture. The tools 42 are also backed up against radial outward movement by means of the lower ring 120 which has 55 an inner cylindrical surface 121 of the same diameter as the cylindrical surface 96. The outer edges of the tools 42 are preferably provided with curved surfaces formed on the same radius as the cylindrical surfaces 96 and 121 so as to be backed-up and guided thereby. The ring 120 is 60 a pressed fit and surrounds the downwardly projecting webs 94, the lower portion 123 of the ring serving to back up the tools laterally opposite the work piece W during a cutting operation. The ring 120 is secured to the annular member 90 by a plurality of screw devices 122 which extend through suitable bores in the ring 120 and into screw-threaded engagement with tapped 65 holes in the member 90.

The arbor supporting member 110 has a central hub 111 provided with a bore 112 in which the arbor 64 is positioned. The arbor is secured against rotary movement by means including a pin 113 carried by the arbor and extending ra-

dially into a suitable recess in the hub 111. The arbor is secured against longitudinal movement by means of a washer 114 and a screw device 115 on the upper end of the arbor positioned in an enlarged portion of the bore 112, and an enlarged splined portion 64' on the lower end of the arbor. Preferably, a ball detent 116 urged outwardly by means of a spring 117 is provided on the splined portion of the arbor for detachably holding the work blank W thereon. The arbor supporting member 110 has a plurality of webs 118 extending radially and outwardly therefrom, as shown most clearly in Fig. 7. At their upper ends these webs are of sufficient length to overlie the annular member 90 so that the arbor supporting member 110 may be secured thereto by means of a plurality of screw devices 119. The intermediate portions of the webs 118 which lie within the annular member 90 are of sufficient length to engage the inner cylindrical wall 96 thereof. The lower portions of webs 118 are relatively short and project outwardly into abutting relation with the webs 94 of the annular member 90. As shown most clearly in Fig. 7, the inner portions 118' of the webs 118 are shaped somewhat in the form of gear teeth but slightly narrower to provide clearance for the teeth of the broaching tool. The intermediate portions 118'' of the webs have side surfaces forming guideways for the broaching tools, whereas the outermost portions of the webs 118 are narrower so as to provide clearance between the webs and the broaching tools. The webs 94 on the annular member 90 are wedge shaped as shown in the left hand half of Fig. 7 and are of sufficient width so that their side surfaces provide guideways for the broaching tools 42.

In order to provide cutter coolant to the broaching tools at the point of engagement with the work blank, a cutter coolant supply pipe 130 extends downwardly from the upper portion of the frame 20, through an opening 131 in the head 29 and into communication with the enlarged upper portion of the bore 112 (Fig. 3) of the hub 111. The hub is provided with a plurality of radially extending ports 132, one for each broaching tool 42, which receive coolant for the pipe 130 and discharge it into the inner portions of the guide slots formed by the web portions 118' so that the coolant may flow downwardly onto the work blank.

The invention as disclosed herein is also provided with means for removing finished work pieces from the arbor 64 and discharging them from the machine through a chute 140 (Fig. 2). This means includes a pair of fingers 141 (Figs. 3, 5 and 6) which extend through diametrically opposite slots 142 in the lower portion of the ring 120 and are pivoted on pins 143. The inner ends of these fingers overlie tooth portions of the work blank W, whereas the outer ends of the fingers are normally spring pressed downwardly by means of plungers 144 backed up by coil springs 145, the plungers and coil springs being mounted in blocks 146 suitably secured to the work plate 34. The fingers 141 are arranged to be pivoted to eject a finished work piece upon completion of the broaching operation by means of a pair of vertical slide rods 147 mounted in bushings 148 in a plate 149 (Figs. 1 to 3) which is mounted on a bracket 189 secured to the wall 23 of the frame 20. The rods 147 are aligned vertically with the ears 82 of the tool clamping members 76, with the result that as the broaching tools approach their uppermost portion wherein the

cutting stroke is completed, the ears 82 engage the lower ends of the rods 147 and move them upwardly, thus causing the inner ends of the fingers 141 to eject the finished work blank W downwardly. The work blank then drops down through the opening in the bushing 75, which is preferably beveled at 75', to facilitate the passage of the finished gear therethrough. The gear is then directed into the chute 140 by means of a pivoted deflector 150 which is pivotally mounted on depending portions 151 of the bracket 189 by means of a rod 152. This deflector is movable from an inoperative position, as shown in full lines in Figs. 1 and 2, to an operative position, as shown in dotted lines in Fig. 2, in which position it functions to arrest the downward movement of the finished gear and to direct the gear into the discharge chute 140. In order to operate the deflector 150 in properly timed relation with the work ejecting means, the deflector is provided with an ear 153 (Fig. 2) which extends rearwardly from the upper end thereof adjacent the pivot rod 152 and is connected to the lower end of a vertically extending rod 154 by means of a pin 155. This rod is normally held in its lower position (in which position the deflector is inoperative) by means of a coil spring 156 which surrounds the lowermost portion of the rod and is compressed by engagement with a lower surface on the plate 149. The rod 154 extends upwardly through a suitable opening in the head 29 and at its upper end carries a collar 157 suitably secured thereto. As the broaching tools reach the upper end of their broaching stroke, at which time the head 29 is at the upper end of its stroke, the rod 154 is raised so as to pivot the deflector 150 to the dotted position shown in Fig. 2. The raising of rod 154 is accomplished by means of a coil spring 158 which surrounds the upper portion of the rod 154 below the collar 157 and above the horizontally extending portion 29' of the head.

In the form shown in the drawings (Figs. 1 and 3), each cylinder 33 is in the form of a tubular member clamped intermediate a lower cylinder head 170 and an upper cylinder head 171 by means of a plurality of bolts 172 which extend through openings 173 in the heads 170 and openings 174 in the heads 171 and into screw-threaded engagement with the work plate 34. The bolts 172 also serve to secure the entire cylinder structure to the work plate. The piston rod 32 extends upwardly through an opening 175 in the head 171 and through a bushing 176 and has a reduced upper end 32' forming a shoulder 177 which fits against the lower surface of the tool head 29. Nuts 178 (Fig. 1) are threaded on the upper ends of the reduced portions 32' so as to secure the piston rods rigidly to the tool head.

In order to guide the upper ends of the tools 42, principally when they are disengaged from the tool holder 40, a split-ring or bushing 185 (Fig. 3) is mounted in a suitable opening in the plate 149 and provided with a flange 186 overlying said plate. As shown most clearly in the left hand portion of Fig. 6, the bushing 185 is provided with radially extending slots 187 which act as guideways for the tools 42. Preferably, these slots are slightly wider than the thickness of the tools so that the tools move freely therein.

The lower portion of the machine may be partly enclosed by means of shields 188 and 189 (Figs. 2 and 8), extending inwardly from the front side edges of the frame 20, around the cylinders 33

and rearwardly into engagement with the wall 23.

Operation

The operation of the machine will now be described. As illustrated in the drawings, and particularly in Figs. 1 to 3, the machine is shown with a preformed gear blank W already attached to the work arbor 64 and the elevator 63 has already moved upwardly to place the upper ends 41 of the broaching tools 42 within the tool holder 40. The tools then extend upwardly through the guide slots 187 in the bushing 185. Upon movement of the head 29 upwardly (caused by actuation of the pistons 31 by a suitable fluid), the elevator device continues its upward movement for a short distance until the upper ends of the tools are clamped by the segmental jaws 51 which move inwardly to clamping position by the action of cam surface 58 against cam surfaces 57. The tool head then continues its upward movement independently of the elevator and the tools, guided by the guideways on the members 90, 110 and 120, cut the teeth on the work blank. Upon the completion of the broaching operation, the ears 82 on the clamping members 16 engage the rods 147 and move them upwardly to pivot the fingers 141 and eject the fingers clear from the splined portion of the work arbor. Preferably, the upper ends of the rods 147 are provided with adjustable screw and nut devices 147' to facilitate accurate adjustment thereof. The finished gear, upon dropping through the opening in the bushing 75, strikes the deflector 150 which has in the meanwhile been pivoted from the full line position of Fig. 2 to the dotted line position thereof. The finished gear then passes out through the chute 140.

The tool head 29 is then moved downwardly through its return stroke by the reverse operation of the pistons 31 in the cylinders 33 and during this return stroke carries the broaching tools 42 downwardly until the bushing 75 engages the elevator 63. The tool head and elevator then move downwardly simultaneously for a short distance, during which time the tool head clamping ring 59 is actuated by the pins 62 (Fig. 3) and raised relatively to the tool head to the position shown in Fig. 3. Continued downward movement of the elevator then disengages the broaching tools from the tool holder 40, the elevator carrying the tools downwardly until the upper ends thereof are below the splined portion of the work arbor 64 but still engaged in the slots 187 of bushing 185. When the elevator reaches this lowermost position, the operator of the machine may place a new work blank on the work arbor, after which the cycle of operation may be repeated by causing the elevator to rise and engage the upper ends of the broaching tools with the tool holder 40.

The fluid supply and control means for the hydraulic actuation of the tool head and elevator cylinders have not been illustrated and described, since such means are old and well known in this art and form no part of the present invention.

By providing a machine as disclosed herein with a tool guiding and work supporting fixture having tool guideways laterally opposite the portions of the work blank to be cut, the invention produces a machine capable of cutting gears and other toothed elements with a high degree of accuracy. The broaching tools are effectively backed up by the ring 120 so as to prevent out-

ward movement thereof and are accurately guided by the webs 94 so as to obtain proper angular spacing of the teeth on the gear. Furthermore, the invention provides a novel means for mounting the broaching tools in predetermined positions on the bushing 75 whereby the handling of the tools as a group is facilitated. The provision of means for ejecting the finished work blank and discharging it from the machine through the chute 40 (which may lead to a suitable hopper or conveyor (not shown) enables the operator to devote his entire attention to the re-loading and starting of the machine. Thus, in a machine having automatic means for controlling the reciprocation of the tool head and elevator, the operator may after loading the machine start the machine and then return only after the finished gear has been discharged.

An important feature is the provision of a broaching tool assembly wherein a plurality of broaching tools are secured together in angularly spaced relation by a clamping means associated with the tail ends thereof, the clamping means being provided with an opening therethrough which permits a finished work piece to pass out. In this way, a gear or similar element may be formed during a single stroke of the broaching tools, and it is not necessary for the tools to pass back over the finished surfaces of the work piece.

Throughout the specification, the term "gear" has been used for purposes of illustration, and it is intended by the use of this term both in the description and claims to include other toothed or splined elements as well.

I claim as my invention:

1. A broaching machine having, in combination, an upright frame, a horizontal work plate secured to said frame intermediate the ends thereof, a broach supporting head slidably mounted on said frame above said work plate, a broach handling elevator device vertically movable with respect to said frame below said work plate, means on said head for simultaneously chucking a plurality of bar-like broaching tools spaced angularly in position to cut the teeth of a gear, means for reciprocating said head, means for securing the lower ends of said tools together in angularly spaced relation including an annular member having a central opening sufficiently large to permit a finished gear to pass therethrough, means for ejecting the work blank from said arbor upon completion of the cutting operation comprising a plurality of fingers pivotally mounted on said work plate with their inner ends overlying teeth on the finished gear and means operable by the broach clamping device for pivoting said fingers upon completion of the cutting operation of the broaching tools, a gear receiving chute extending laterally of said frame below said work plate, a deflector device pivotally mounted on said frame for engaging finished gears and deflecting them into said chute, and means operable by said head as it approaches the upper end of its movement for swinging said deflector device into position vertically under the work plate for engaging a finished gear falling through said annular member and directing it into said chute.
2. A broaching machine having, in combination, an upright frame, a broach supporting head slidably mounted on the upper portion of said frame, a broach handling elevator device vertically movable opposite the lower portion of said frame, means on said head for simultaneously

chucking a plurality of bar-like broaching tools spaced angularly in position to cut the teeth of a work element, means for reciprocating said head, a clamping device for securing the lower ends of said tools together in angularly spaced relation including an annular member having a central opening sufficiently large to permit a finished work element to pass therethrough, a downwardly projecting work element arbor supported on said frame for receiving a work element, and means for ejecting the work element from said arbor upon completion of the cutting operation comprising a finger having a part thereof overlying a portion of the finished element and means operable by the broach clamping device for moving said finger upon completion of the cutting operation of the broaching tools.

3. A broaching machine having, in combination, an upright frame, a broach supporting head slidably mounted on the upper portion of said frame, means on said head for simultaneously chucking a plurality of bar-like broaching tools spaced angularly in position to cut the teeth of an element, means for reciprocating said head, a clamping device for securing the lower ends of said tools together in angularly spaced relation including an annular member having a central opening sufficiently large to permit a finished element to pass therethrough, a work element arbor supported on said frame and in a position centrally of said tools, and means for ejecting the finished element from said arbor upon completion of the cutting operation.

4. A broaching machine having, in combination, an upright frame, a broach supporting head slidably mounted on said frame above said work plate, means on said head for simultaneously chucking the upper ends of a plurality of bar-like broaching tools spaced angularly in position to cut the teeth of a gear, means for reciprocating said head, a clamping device for securing the lower ends of said tools permanently together in angularly spaced relation having a central opening sufficiently large to permit a finished gear to pass therethrough, a work blank arbor projecting downwardly from said work plate, means for ejecting the finished gear from said arbor upon completion of the cutting operation, a gear receiving chute extending laterally of said frame below said work plate, a deflector device pivotally mounted on said frame for engaging finished gears and deflecting them into said chute, and means operable by said head as it approaches the upper end of its movement for swinging said deflector device into position vertically under said clamping device for deflecting a finished gear falling through the central opening of said device.

5. A broaching machine having, in combination, a frame, a work plate secured to said frame intermediate the ends thereof, a broach supporting head slidably mounted on said frame on one side of said work plate, means on said head for simultaneously chucking the leading ends of a plurality of bar-like broaching tools spaced angularly in position to cut the teeth of a gear, means for reciprocating said head, a clamping device for clamping the tail ends of said tools permanently in angularly spaced relation including a member having a central opening sufficiently large to permit a finished gear to pass therethrough, a work blank arbor projecting from said work plate for releasably holding a work blank, and means for ejecting the work blank from said arbor upon completion of the cutting

operation so that it moves out through the central opening of said clamping device.

6. In a machine for broaching gears having a plurality of tools spaced about a circle each adapted to operate on a work blank to form the space between two adjoining teeth during a single stroke of the tools, in combination, a work plate, a tool guiding and work supporting fixture secured to said plate comprising a member having an annular rim and a plurality of webs extending radially inwardly and downwardly from the lower portion of said rim to form radial guide slots for said tools, a ring surrounding said downwardly projecting webs and having an inner surface cooperating with the inner surface of said annular rim to back-up the tools as they pass through said slots and prevent movement thereof radially outward, a hub positioned centrally of said annular rim having outwardly extending webs aligned with the webs of said member, means securing the webs of said hub to said member, a work supporting arbor secured centrally of said hub and having a splined work blank receiving portion projecting downwardly therefrom and laterally opposite said ring, and a spring pressed detent device for releasably holding a work blank on said arbor.

7. In a machine for broaching gears and the like having a plurality of tools spaced about a circle each adapted to operate on a work blank to form the space between two adjoining teeth during a single stroke of the tools, in combination, a tool guiding and work supporting fixture comprising a member having a plurality of webs extending radially of the tools to form guide slots for said tools, a ring surrounding said webs and having an inner surface to back-up the tools as they pass through said slots and prevent movement thereof radially outward, a work supporting arbor positioned centrally of said webs and having a work blank receiving portion projecting therefrom and laterally opposite said ring, and means securing said work supporting arbor rigidly to said member.

8. In a machine for broaching toothed elements having a plurality of tools spaced about a circle each adapted to operate on a work blank to form the space between two adjoining teeth during a single stroke of the tools, in combination, a tool guiding and work supporting fixture comprising a member having an annular rim and a plurality of webs extending inwardly and longitudinally from said rim to form guide slots for said tools, a ring surrounding said longitudinally projecting webs and having an inner surface to back-up the tools as they pass through said slots and prevent movement thereof radially outward, a hub positioned centrally of said member having outwardly extending webs aligned with the webs of said member, means securing the webs of said hub to said annular rim, and a work supporting arbor secured centrally of said hub and having a work blank receiving portion projecting therefrom laterally opposite said ring.

9. In a machine for broaching toothed elements having a plurality of tools spaced about a circle each adapted to operate on a work blank to form the space between two adjoining teeth during a single stroke of the tools, in combination, a tool guiding and work supporting fixture comprising a member having an annular rim and a plurality of webs extending radially inwardly and longitudinally from one end of said rim to form guide slots for said tools, a ring surrounding said longitudinally projecting webs and having an inner

surface cooperating with the inner surface of said annular rim to back-up the tools as they pass through said slots and prevent movement thereof radially outward, a hub positioned centrally of said member having outwardly extending webs aligned with the webs of said member, said webs on the hub having portions abutting the inner ends of said first mentioned webs and other portions overlying said first mentioned webs, means securing the outer ends of the webs of said hub to said annular rim, and a work supporting means secured centrally of said hub and having a work blank receiving portion projecting therefrom laterally opposite said ring.

10. A broaching machine having, in combination, a frame, a tool guiding and work supporting fixture mounted on said frame intermediate the ends thereof and having a work arbor, and tool guiding and backing surfaces laterally opposite a work blank receiving portion of the work arbor, a broach supporting head slidably mounted on said frame to one side of said fixture, means for reciprocating said head, a broaching tool holder carried on said head and adapted to chuck the leading ends of a plurality of annularly arranged and parallel broaching tools for a pull broaching operation, means for clamping the tail ends of said tools in angularly spaced relation, a movably mounted device for handling said tools from the tail ends thereof, and guide means for said tools mounted on said frame between said fixture and movably mounted device in position to engage the tools throughout their stroke including an annular member having radially extending slots through which the broaching tools pass.

11. A broaching machine having, in combination, a frame, a tool guiding and work supporting fixture mounted on said frame intermediate the ends thereof and having a work arbor and tool guiding and backing surfaces laterally opposite a work blank receiving portion of the work arbor, a broach supporting head slidably mounted on said frame to one side of said fixture, means for reciprocating said head upon said frame, a broaching tool holder carried on said head and adapted to chuck the leading ends of a plurality of annularly arranged and parallel broaching tools for a pull broaching operation, means for clamping the tail ends of said tools in angularly spaced relation, and guide means for said tools mounted on said frame in position to engage the tools throughout their stroke.

12. A broaching machine having, in combination, a frame, a tool guiding and work supporting fixture mounted on said frame intermediate the ends thereof and having a work arbor and tool guiding and backing surfaces laterally opposite a work blank receiving portion of the work arbor, a broach supporting head slidably mounted on said frame to one side of said fixture, means for reciprocating said head upon said frame, a broaching tool holder carried on said head and adapted to chuck the leading ends of a plurality of annularly arranged and parallel broaching tools for a broaching operation, means for clamping the trailing ends of said tools together in angularly spaced relation, and a movably mounted device for handling said tools from the clamped ends thereof.

13. A broaching machine having, in combination, an upright frame, a tool guiding and work supporting fixture mounted on said frame intermediate the ends thereof and having a downwardly projecting work arbor and tool guiding and backing surfaces laterally opposite the work

blank receiving portion of the work arbor, a broach supporting head slidably mounted on said frame above said fixture, means for reciprocating said head vertically upon said frame, a broaching tool holder carried on said head and adapted to chuck the upper ends of a plurality of annularly arranged and parallel broaching tools for a pull-up broaching operation, and means for clamping the lower ends of said tools together in angularly spaced relation.

14. A broaching machine having, in combination, an upright frame, a tool guiding and work supporting fixture mounted on said frame intermediate the ends thereof and having a downwardly projecting work arbor and tool guiding and backing surfaces laterally opposite the work blank receiving portion of the work arbor, a broach supporting head slidably mounted on said frame above said fixture, means for reciprocating said head vertically upon said frame, a broaching tool holder carried on said head and adapted to chuck the upper ends of a plurality of annularly arranged and parallel broaching tools for a pull-up broaching operation, a vertically movable elevator device for handling said tools from the lower ends thereof, and guide means for said tools mounted on said frame below said fixture in position to engage the tools throughout their stroke and having radially extending slots through which the broaching tools pass.

15. A broaching machine having, in combination, a frame, a tool guiding and work supporting fixture mounted on said frame intermediate the ends thereof and having a work arbor and tool guiding and backing surfaces laterally opposite the work blank receiving portion of the work arbor, a broach supporting head slidably mounted on said frame on one side of said fixture, means for reciprocating said head vertically upon said frame through broaching and return strokes, a broaching tool holder carried on said head and adapted to chuck the leading ends of a plurality of annularly arranged and parallel broaching tools for a pull broaching operation, and means having a central opening through which the finished work blank may pass for clamping the tail ends of said tools together in angularly spaced relation.

16. A broaching machine having, in combination, a frame, a broach supporting head slidably mounted on said frame adjacent one end thereof, a broach handling device slidably mounted on the other end of said frame, means on said head for simultaneously chucking a plurality of broaching tools spaced angularly in position to cut the teeth of an externally toothed element, means for reciprocating said head, a clamping device for securing the tail ends of said tools together in angularly spaced relation including a member having a central opening sufficiently large to permit a finished element to pass therethrough, and means for supporting a work blank in position to be operated upon by said tools.

17. A broaching machine having, in combination, a frame, a broach supporting head slidably mounted on said frame adjacent one end thereof, a broach handling device slidably mounted on the other end of said frame, means on said head for simultaneously chucking a plurality of broaching tools spaced angularly in position to cut the teeth of an externally toothed element, means for reciprocating said head, a clamping device for securing the tail ends of said tools together in angularly spaced relation including a member having a central opening sufficiently

large to permit a finished element to pass therethrough, means for supporting a work blank in position to be operated upon by said tools, and means for moving laterally a finished element after passing through said central opening.

18. A broaching machine having, in combination, means for simultaneously chucking a plurality of bar-like broaching tools spaced angularly in position to cut a toothed element, means for supporting a work blank and guiding the tools including a backing ring surrounding the work blank, a plurality of broaching tools spaced angularly with cutting edges on their inner surfaces in position to cut a toothed element and having curved surfaces on their outer edges conforming to the radius of said backing ring, a clamping device for securing the tail ends of said broaching tools together as a unit in angularly spaced relation, said clamping means having a central opening through which a finished work blank may pass, and means for causing relative feeding movement between the tools and work blank.

19. A broaching machine having, in combination, a frame, a broach supporting head slidably mounted thereon, means on said head for simultaneously chucking a plurality of bar-like broaching tools spaced angularly in position to cut a toothed element, means for supporting a work blank and guiding the tools including a backing ring laterally opposite the work blank and a plurality of broaching tools spaced angularly with cutting edges on their inner surfaces in position to cut a toothed element and having curved surfaces on their outer edges conforming to the radius of said backing ring.

20. A broaching machine having, in combination, a frame, a broach supporting head slidably mounted on said frame, means on said head for detachably and simultaneously chucking the leading ends of a plurality of broaching tools spaced annularly and in substantially parallel relation to cut the teeth of a toothed element, means for supporting said tools in such annularly spaced and substantially parallel relation when detached and separated from said chucking means to enable a work blank to be inserted into the space between the chucking means and the detached ends of the tools, means for supporting the work blank in operative relation to the tools, and means for moving said head when the tools are engaged by the chucking means to perform a pull broaching operation on the work blank.

21. A broaching machine having, in combination, a frame, a broach supporting head slidably mounted on said frame, means on said head for simultaneously chucking the leading ends of a plurality of bar-like broaching tools arranged in annularly spaced and substantially parallel relation to cut the teeth of a toothed element, means for reciprocating said head, means for supporting said broaching tools in such annularly spaced and substantially parallel relation when released and separated from said chucking means to permit the insertion of a work blank intermediate the leading ends of the tools and the chucking means, a work element support on said frame in a position to receive the work element when the tools are separated from the chucking means, and means adjacent the work element support forming guides for the sides and back of each tool during the cutting operation.

22. A broaching machine having, in combina-

tion, an upright frame, a horizontal work plate secured to said frame intermediate the ends thereof, a broach supporting head slidably mounted on said frame above said work plate, means on said head for simultaneously chucking the leading ends of a plurality of bar-like broaching tools arranged in annularly spaced and substantially parallel relation to cut the teeth of a toothed element, said means being releasable to permit separation of the broaching tools therefrom, means including a broach handling elevator device vertically movable with respect to said frame below the work plate for separating the tools from the chucking means and withdrawing them below the work plate to permit a work blank to be positioned between the work plate and the broaches, and means for actuating said broach supporting head through a pull broaching operation with the broaches engaged by the chucking means.

23. A broaching machine having, in combination, an upright frame, a horizontal work plate secured to said frame intermediate the ends thereof, a broach supporting head slidably mounted on said frame above said work plate, means on said head for simultaneously chucking a plurality of bar-like broaching tools arranged in annularly spaced and substantially parallel relation in position to cut the teeth of a toothed element, said means being releasable to permit separation of the broaching tools therefrom, means including a broach handling elevator device vertically movable with respect to said frame below the work plate for separating the tools from the chucking means and withdrawing them below the work plate to permit a work blank to be positioned centrally of the branch annulus, means on said work plate for supporting the work blank and for backing up the tools during a broaching operation, and means for actuating said broach supporting head through a pull broaching operation with the broaches engaged by the chucking means.

24. A broaching machine having, in combination, a frame, a first broach supporting head slidably mounted on said frame, means on said head for simultaneously chucking a plurality of bar-like broaching tools arranged in annularly spaced and substantially parallel relation in position to cut teeth on a toothed element including means for releasing said tools, a second broach supporting head slidably mounted on said frame including means for holding said broaching tools in annularly spaced and substantially parallel relation when separated from said chucking means, a work blank support on said frame positioned to mount a work blank between the leading ends of said tools and said first head when the tools are separated from the chucking means, means for actuating said second broach supporting head to move the broaches into engagement with said chucking means for a broaching operation and to withdraw the broaches from the chucking means upon completion of a broaching operation, and means for actuating said first mentioned supporting head in one direction through a broaching operation and to separate the trailing ends of the broaches from said second supporting head whereupon the finished work blank may pass out from between the trailing ends of the broaching tools.
